Specification for Design.

Patented Aug. 2, 1921.

Application filed January 20, 1921. Serial No. 438,755. Term of patent 14 years.

To all whom it may concern:

Be it known that I, ISIDORE H. LAPIDUS, a citizen of the United States, residing at New York city, in the county and State of New York, have invented a new, original, and ornamental Design for Jewelry—namely, finger-rings or articles of similar nature—of which the following is a specification, reference being had to the accompanying drawing, forming a part thereof.

Figure 1 is a side elevational view of a finger ring showing my new design.

Fig. 2 is an edge view thereof.

Fig. 3 is a perspective view thereof.

I claim—

The ornamental design for jewelry—namely, a finger ring or article of similar nature as shown.

In testimony whereof I affix my signature.

ISIDORE H. LAPIDUS.
